UNITED STATES PATENT OFFICE

2,198,405

ELECTRIC CABLE

Otto Cords, Berlin, Germany

Application October 15, 1937, Serial No. 169,311
In Germany October 21, 1936

2 Claims. (Cl. 174—28)

This invention relates to an air-space insulated electric cable, more particularly a high-frequency cable, of the kind described in my prior Patent No. 2,118,005, dated May 17, 1938.

In my prior patent in question I have described an air-space insulated electric cable comprising a central conductor, an outer covering surrounding the said conductor in spacial disposal thereto and comprising helical windings, and helically wound supporting means supporting the said conductor in relation to the said outer covering and disposed between the convolutions of the said windings.

In certain embodiments of this general idea the supporting means for the central conductor consist of threads or tapes which are passed about the conductor and over bars formed by the outer covering, these bars constituting the points of intersection of the preferably oppositely wound tapes of which the outer covering is composed. Owing to the helical winding of the tapes these bars are also disposed along a helical path.

It is the object of the invention to improve generally on air-space insulated cables of this character and to provide a modified design in which the bars about which the supporting threads or tapes are passed can be produced more readily than in the case of my said prior patent.

With this and other objects in view the outer covering consists of a tubular member, the wall of which is furnished with obliquely disposed slots disposed along a helical path and arranged in such spacial disposal to one another that bars are formed between the same about which there can be passed the holding threads or tapes for the conductor.

A tape may be used to form the tubular member, which in this case may have a longitudinal seam. The tube can be formed in the machine employed for the production of the cable, and if desired the longitudinal edges of the tube can be made to overlap. In certain circumstances a connection of the overlapping edges is unnecessary. It is also possible to connect the longitudinal edges of the tube by folding them together, or the connection may be performed by soldering or welding. In the latter case the longitudinal edges of the tube may be allowed to abut endwise one against the other.

The invention is illustrated by way of example in the accompanying drawing, in which

Fig. 1 illustrates diagrammatically a piece of cable according to the invention.

Fig. 2 is a cross-section according to the line 5 II—II in Fig. 1.

Fig. 3 shows a piece of tape, furnished with slots, from which the tubular member is formed.

In the drawing 1 is the central conductor of the high-frequency cable. The outer covering 10 or screen consists of a tubular member 2 having slots 3. As shown in Figs. 1 and 3, the slots are disposed along a helical path about the tube and are so arranged that between the same there are formed bars 4. The central conductor 1 is 15 maintained in spacial disposal to the outer covering by means of the thread or tape 5. This thread or tape is passed about the bars 4 in the manner shown in Fig. 1.

In the particular embodiment shown there is 20 employed a tube having overlapping edges as depicted in Fig. 2. These overlapping edges can be connected if desired by soldering or welding. In Fig. 2 the supporting thread or tape is indicated in broken lines.

What I claim as new and desire to secure by Letters Patent is:

1. In an air-space insulated electric cable, a central conductor, an outer covering surrounding the said conductor in spacial disposal thereto 30 and consisting of a member bent into tubular form and having a longitudinal seam, said tubular member having slots disposed helically in spacial relation to one another to form intermediate bars, and a supporting means for the said conductor passed about the said conductor and over the said bars to hold the said conductor in spacial disposal to the said outer covering.

2. In an air-space insulated electric cable, a central conductor, an outer covering surrounding said conductor in spacial disposal thereto and having slots disposed helically in spacial relation to one another to form intermediate bars, and supporting means passed about said conductor and through said slots over said bars, the 45 said outer covering consisting of a member bent into tubular form and having the edges brought together to form a longitudinal seam, said slots being disposed obliquely of said edges.

OTTO CORDS. 50
